ANGUS D. MCKENZIE, OF MANSFIELD, OHIO, ASSIGNOR TO THE AMERICAN SAFETY NAVIGATION COMPANY, OF CANTON, OHIO, A CORPORATION OF OHIO

BOAT-LAUNCHING DEVICE

Application filed August 4, 1930. Serial No. 472,801.

My invention particularly relates to davits for life boats, and to improvements in devices of this character which are gravity-operated. My improved device is provided with means adapted automatically to unfasten the boat-cover lashings and the boat-body lashings and remove these lashings from the boat concurrently with the outward movement of the davit which commences the boat launching operation. My improvements in boat-launching devices are high slung so as to take up a minimum of deck space. For accomplishing these purposes, I have designed the form of apparatus shown in the accompanying drawings and hereinafter fully described, this apparatus being easily operated, simple in its mechanical make-up, and possessing only a minimum possibility of being jammed or rendered inoperative.

The annexed drawings and the following description set forth in detail certain means embodying the invention, such disclosed means constituting, however, but two of the various forms in which the principle of the invention may be embodied.

In said annexed drawings:

Figure 1 is an end elevation of my improved davit and lashing-releasing construction, associated with a life boat to which the improvements are applicable, the upright or stationary supporting position of the davit and associated elements being shown in full lines and a launching position being shown in broken lines;

Figure 1^a is a view similar to Figure 1, but upon an enlarged scale and in an unlocked position, of certain locking members forming part of the means for holding the davit in normal stationary inoperative position;

Figure 1^b is a view similar to Figure 1^a of said locking members in fastening position;

Figure 2 is a broken side elevation of conventional control mechanism adapted for use with my invention;

Figure 3 is an end elevation of the control mechanism, and the drums and associated gearing shown in Figure 2;

Figure 4 is a front elevation of the apparatus as shown in full lines in Figure 1;

Figure 5 is a fragmentary horizontal sec-

tion, upon an enlarged scale, taken in the plane indicated by the line 5—5, Figure 4;

Figure 6 is a fragmentary plan view, upon an enlarged scale, taken from the plane indicated by the line 6—6, Figure 4;

Figure 7 is a vertical section, taken in the plane indicated by the line 7—7, Figure 6;

Figure 8 is a plan section, taken in the planes indicated by the line 8—8, Figure 1;

Figure 9 is a vertical section, taken in the plane indicated by the line 9—9, Figure 4;

Figure 10 is a fragmentary bottom plan, taken in the plane indicated by the line 10—10, Figure 4;

Figure 11 is a fragmentary vertical section, upon an enlarged scale, taken in the planes indicated by the line 11—11, Figure 8;

Figure 12 is a vertical section, taken in the plane indicated by the line 12—12, Figure 11;

Figure 13 is a fragmentary plan view, upon an enlarged scale, taken from the plane indicated by the line 13—13, Figure 4, the plane from which this view is taken being also indicated by the line 13—13, Figure 15;

Figure 14 is a vertical section, taken in the plane indicated by the line 14—14, Figures 13 and 15;

Figure 15 is a vertical longitudinal section, taken in the plane indicated by the line 15—15, Figures 8 and 13;

Figure 16 is a vertical section, upon an enlarged scale, of some of the elements shown in Figure 9;

Figure 17 is a top plan view of the elements shown in Figure 16;

Figure 18 is an end elevation, similar to the full line view of Figure 1, showing a modified form of fastening means for boat-cover and boat-body lashings and a modified form of means for automatically releasing said lashings upon the commencement of the outward movement of the boom;

Figure 19 is a horizontal section, taken in the planes indicated by the line 19—19, Figure 18;

Figure 20 is an end elevation, upon an enlarged scale, of some of the elements as shown in Figure 18;

Figure 21 is a fragmentary vertical section, upon an enlarged scale, taken in the plane indicated by the line 21—21, Figure 19, and showing the lashings in locked position; and

5 Figure 22 is a section, similar to Figure 21, but showing the lashings in position to be released from the mechanism adapted to retain them in locked position.

10 Referring to the annexed drawings in which the different elements are indicated by the same respective numbers in the several views, upon an upper ship deck 1 is mounted a stanchion 3 which serves as a main support for the boat-launching mechanism and which 15 may be, as a matter of practice, the frame of a deck house. The apparatus is designed to launch the life-boat 5 over the rail 4 of the deck 1 into a position adjacent a lower deck 2 where the boat may be loaded with passengers conveniently and thence lowered into the water.

20 Two pairs of spaced angle bars 7 are secured to the deck 1 and in the upright members of each pair of these angle bars is a 25 horizontally-mounted pivot pin 6. These two pairs of angle bars 7 and the pair of pivot pins 6 serve as supports within which the lower ends of two booms 8 are pivoted. Inasmuch as the construction and operation of 30 both booms 8 are identical, I shall hereinafter describe in detail only one of them. The boom 8 is a substantially vertically-disposed member for the greater part of its length, when in normal stationary position, the upper end 35 9 thereof, however, being sharply curved outwardly toward the plane of the rail 4 of the deck 1, so as to permit the vertical supporting of the life boat 5 from the outer end of the curved boom section 9, the life boat 5 being 40 disposed above the deck 1 substantially parallel with the side of the ship and the inner side of the boat 5 lying under the upper curved section 9, of the boom 8, as will be readily seen and understood. The construction is 45 such as to provide ample head-room between the deck 1 and the boat 5. Secured to the outer face of the main support 3 is a vertical plate 10 having vertical grooves in its outer face which are engaged by rollers 14 mounted upon pivot pins 14' which in turn are 50 mounted in the lower ends of arms 11 of a member 11—12 of bell crank formation which is pivoted upon a pin 13 secured in the boom 8. Upon the member 12 of the bell crank 11— 55 12 are mounted chocks 17 and 18 upon and against which the life boat 5 rests when in normal inoperative position shown in full lines in Figure 1. In order that the life boat 5 may be prevented from lifting up, the plate 60 10 is formed with outwardly projecting hooks 15 adapted to engage the outer side of the rollers 14, as shown in Figure 1. As is evident from the broken line showing in Figure 1, the bell crank 11—12 swings upon the pivot 13, 65 during the outward movement of the boom 8,

the weight of the element 12 and the chocks 17 and 18, and associated parts as compared with the weight of the element 11, being sufficient to insure such swinging movement of the bell crank. By reason of this relative pivotal movement between the boom 8 and the bell crank 11—12, the element 12 strikes the deck 1, after the boom 8 has completed its outward movement. But before this happens a stop bracket 16 secured to the element 12 strikes the boom 8, as plainly shown in broken line position in Figure 1, so that thereafter the bell crank 11—12 has no movement relative to the boom 8 but swings downwardly rigidly with the latter until the bottom of the element 12 strikes a thrust block 48 secured to the deck 1. During this downward pivotal movement of the bell crank 11—12, the rollers 14 ride upwardly in the grooves 10', hugging the plate 10 closely until the stop bracket 16 strikes the boom 8.

70 The life boat 5 is supported and operated through the medium of a cable 20. The outer end of this cable is secured to a block 19 fixed in the life boat 5 substantially midway the width of the life boat and as high as is practicable. Secured to the cable 20 and adjacent the lower face of the curved outer portion 9 of the boom 8 is a stop block 21 which prevents the raising of the life boat 5 75 beyond a certain predetermined height relative to the top of the boom. This stop block 21 on the cable 20 contacts tightly with the under face of the curved portion 9 of the boom 8, when the boom is moving from the full line position shown in Figure 1 to the broken line position shown therein, but is positioned a short distance from the said under face of the portion 9 and the boom 8, when the boat 5 is resting upon the chocks 17 and 18, and the boom is in its normal upright inoperative position. A detailed description 80 will be hereinafter given relative to these actions of the stop block 21. The cable 20 is continued over a pulley 22 secured adjacent the outer end of the boom portion 9 and thence over a pulley 23 secured to the boom at about the top of the vertical portion thereof and thence around a sheave 24 mounted on the main support 3, whence the cable 20 passes to a suitable control mechanism housed in a casing 25. This control mechanism is shown in detail in Figures 2 and 3 and consists of hoisting apparatus adapted to lower and lift the boat 5 at the desired speed. This control mechanism is common to the launching elements associated with the two booms 8, one set of these elements being associated with each end of the life boat 5, the control mechanism being adapted to take in or play out the two cables 20 in equal amounts. No claim is 90 made to any invention in the control mechanism and the conventional form thereof shown in Figures 2 and 3 comprises a motor 26 to whose shaft is fixed a pinion 27 engag- 95 100 105 110 115 120 125 130

ing a spur gear 28 secured to one end of the shaft 29 mounted in the control mechanism housing 25, a pinion 30 being secured to the opposite end of the shaft 29, and engaging one of a pair of intermeshing gears 31 secured respectively to a pair of shafts 32 to which are secured drums 33 upon which the two cables 20 are wound. Suitable mechanism is thus provided for the desired gear reductions, and the paying-out of the drawing-in of the cables 20, and other actions necessary to such control mechanism.

Extending between and pivotally mounted in the two main supports 3 is a shaft 34, clearly shown in Figure 8, upon whose ends projecting from the main supports 3 are mounted latches 36, one of which is formed with an operating handle 35, clearly shown in Figure 1. The latches 36 are utilized to lock the davit in stationary upright position and are operated as follows: Secured at one end to and upon one end of a pin 39 mounted in the boom 8 is a dog 37 adapted to engage a notched portion 38 of the latch 36, the latter being further held in locked position by an additional dog 40 pivoted at one end to a bracket 50 secured to the main support 3. Secured to the bracket 50 and extending inwardly of the boom is a projection 41 formed with an upwardly-projecting inner-end shoulder 44 adapted to engage with a tooth 43 formed upon a cam-shaped member 42 secured to, and intermediately of the ends of, the pin 39 and within the confines of the boom 8. The purpose of this construction will be hereinafter fully described. A counterweight 38 forming one end portion of the dog 37 is adapted, when the dog 37 is released from the latch 36, to throw the dog 37 up into substantially a vertical position, such as shown in broken lines in Figure 1, and also shown in Figure 1^a, whereby when the boom 8 is being lifted into vertical stationary position, the dog 37 will not interfere with or foul other parts of the locking mechanism. The cam-like member 42 is formed upon one side with an extended portion 53 adapted, as the boom 8 is being raised, to contact the outer edge 51 of the member 41 and rotate the member 42 so as to cause the tooth 43 to loosely engage the shoulder 44 and assume the position clearly shown in Figure 1^b. Thus, as the boom 8 is lifted to its extreme upright position, a lock is automatically provided for holding the boom in this position, which lock prevents any further outward movement of the boom after the dog 37 and latch 36 and the dog 40 have been respectively engaged, and after the boom has moved outwardly a slight distance following the interlocking of these fastening members. In order to obviate the possible inward movement of the boom 8 when it is locked, I provide a holding screw 47 threaded through a block 46 mounted on the bracket 54, this screw 47 bearing against a wear plate 45 secured to the outer side of the boom 8. The counterweight 38, of course, tends to throw the dog 37 out of locking position and it quickly does thus act, to move the dog 37 out of the way, after the dog 40 has been unlocked and after the operating handle 35 is actuated to release the latch 36. This actuation of the handle 35 permits the automatic unlocking of the shoulder 44 and the tooth 43, under the action of the counterweight 38, and the immediate starting of the outward rotation of the boom and the dropping away of the load-support 11-12 from under the life boat 5, the stop block 21 quickly contacting with the under surface 52 of the top end of the boom. The action thereafter is controlled by the mechanism 25 controlling the play of the cables 20.

Referring particularly to Figure 4, a boat cover 60 is secured by cover lashings 62 to the upper edge of the boat and throughout the perimeter thereof, these cover lashings 62 being formed with eyes 63 adjacent their lower ends by means of which they are fastened, as also automatically released when necessary, as will be hereinafter fully explained. The boat cover 60 is suspended from the outer end of the boom 8 by ropes 61, as clearly shown in Figure 4 and in broken lines in Figure 1. Boat lashings, consisting of cables 64, are also provided, Figure 9, which are passed at their upper ends around and over the gunwales 87 of the boat and which have eyes 65 by means of which they are fastened and automatically released. As clearly shown in Figures 4 and 8, there are a comparatively large number of opposed pairs of the cover lashings 62 and two pairs of opposed boat lashings 64. I shall now describe the means for fastening these cover and boat lashings and for automatically releasing the same, concurrently with the commencement of the outward movement of the boom 8.

Secured to the two arms 12 of the bell cranks 11-12 and transversely of the booms 8 are an inverted channel member 71 and an underlying plate 79, the channel member 71 being formed with a plurality of spaced pairs of longitudinally spaced upwardly extending eyes 86, one spaced pair of such eyes for each opposed pair of cover and boat lashings. Extended through this channel member 71 is a slideable rod 66 formed with a plurality of raised curved hook members 67, extended substantially parallel with the rod 66, one of which hooks is designated 68 and is somewhat longer than the other hooks, in the form of device illustrated in the accompanying drawings. It is not absolutely necessary that one of these hooks be longer than the others inasmuch as the purpose of this construction can be accomplished by hooks all of the same size, as will be hereinafter fully described.

These hooks 67 and 68 pass through the eyes 86 of the channel member 71 adjacently beneath the lower faces of the upper portions of said eyes 86. When the cover lashings 62 and 5 the boat lashings 64 are fastened, the respective eyes 63 and 65 at the outer ends of said lashings are engaged by these hooks 67 and 68, the long hook 68 engaging the eyes of one of the pairs of boat lashings 64, the particular 10 purpose of which will be hereinafter fully explained. The upper ends of the two pairs of boat lashings 64 are passed around the gunwale 87 of the boat 5 and tightened around the boat by the following means. The 15 inner end of each boat lashing 64 is secured to a tightening member; Figures 9, 16, and 17, having a handle 89 and formed with an extended internally-threaded hub member 90. This hub member 90 co-operates with an externally-threaded sleeve 88 having a bearing portion 88' contacting with a wear plate 92 secured to the top of the boat gunwale 87. Seated against the inner end of the tightening 20 member 89—90 is a clevis 91 within whose 25 arms is mounted a pin 94. Around the two pins 94 at the ends of the two opposed boat lashings 64 is passed a strap 93 formed with a buckle 102. A cable 95 secured to the strap 93 serves to attach this boat lashing structure 30 to the under side of the cover 60. It is evident that after the eyes 65 of the boat lashing 64 have been engaged by the hooks 67, the boat lashings can be tightened around the boat by revolving the handles 89 and thus 35 moving the two inner ends 91 of the lashing 64 inwardly of the top of the boat by reason of the travel of the sleeve 90 upon the engaging member 88. The endless strap 93 serves to connect together the two inner ends of the 40 tightened lashings 64 and also affords means by which the cable 95 can suspend the pair of lashings 64 from the cover 60. The wear plate 92 also serves as a contact surface for the movement of the boat lashing 64 over the 45 surface of the gunwale 87. When fastening the boat 5 either the outer or inner lashing cable 64 can be tightened to slide the boat 5 one way or the other as is required properly to locate it in its chocks 17 and 18. No sliding 50 movement of the boat 5 can take place in these chocks after both lashing cables 64 have been tightened. However, in a rough sea, the boat 5 could roll outward over the chock block 18. To obviate this rolling movement 55 of the boat under these circumstances, the inside lashing cable 64 is carried over a pulley 96 so that the inside gunwale 87 is prevented from lifting or, in other words, from rotating about the chock block 18. Rotation of 60 the boat 5 in the other direction is prevented by the chock block 17. Thus, any untoward movement of the boat 5 in its chocks is prevented when both the lashing cables 64 are tight.

65 The invention is designed, under most con-

ditions, automatically to release the cover and boat lashings and move them to non-fouling and non-interfering positions upon the commencement of the outward movement of the boom 8 which is permitted by the release of 70 the latch 36. In order that this may be accomplished I mount a pulley 72 upon an angular end 73 of the slidable rod 66 and pass around this pulley a cable 69 fastened at one end 70 to the channel member 71. From the pulley 72 the cable 69 is passed around a second pulley 74 secured adjacent the opposite end of the channel 71, whence the cable 69 passes around a third pulley 75 anchored by a holding member 76 which is formed with an eye 77 engaged by the long hook 68 of the rod 66. Then the cable 69 is secured at its other end to a point 78 upon the main support 3. It is evident that immediately upon the commencement of the outward movement of the boom 8, the lashing-operating cable 69 tightens and pulls upon the angular end portion 73 of the slidable rod 66, moving this rod 66 longitudinally of the channel 71 and moving the hooks 67 from the lashing eyes 63 and 65, 90 the eyes intersected by the long hook 68 being the last ones thus released. Upon such release of the lashings, the cover lashings hang downwardly from the plurality of straps 101 forming part thereof and by means of which each cover lashing is fastened to the cover 60, and the boat lashings 64 depend loosely from and vertically of the boat gunwales 87. It is evident that without some means for releasing the tension upon the cable 69, the latter would interfere with the downward movement of the boom, or be broken, so that I have provided means for obviating this tension through the pulley 75 normally anchored to the slidable rod 66 by the holding member 76. When the eye 77 of this holding member 76 is released from the long hook 68, the pulley 75 is permitted to drop downwardly toward the deck 1 and thus provide plenty of free cable 69 to permit the continued downward movement of the boom 8 until the arm 12 strikes the thrust block 48. It is further evident that upon the downward movement of the boat 5 relative to the boom 8, which takes place when the arms 110 12 of the bell cranks 11—12 strike the thrust blocks 48 upon the deck 1, the lashings 62 and 64 are suspended from the cover 60, as clearly shown in Figure 1, the stop block 21 upon the boat-operating cable 20 meanwhile passing through a hole 80 formed in the top of the boat cover 60.

115 Since the purpose of the long hook 68 is to insure the release of the anchored pulley 75, after the release of the lashing eyes 63 and 65, it is evident that this purpose might be served by so threading the eye 77 of the pulley 75 upon a hook 67 of normal length so as to provide for such comparatively later 120 release of the pulley eye 77. However, my 125 130

preferred method of accomplishing this purpose is to provide the comparatively long hook 68 whose construction and operation has been described.

- 5 The construction shown and described also allows for manual operation of the lashing-release devices, when required. The automatic tripping of these release devices will operate satisfactorily up to a list of 15 to 20 70 degrees, beyond which list there is so little power in the booms 8 that they cannot pull the bent rod 66. Therefore, under such conditions or in other necessary or desired circumstances the cable 69 can be manually 75 pulled, before releasing the davit, and then the boat 5 can be launched up to a list of from 25 to 28 degrees.

In the form of lashing-securing and releasing means shown in Figures 18 to 22, including 80 a tubular member 110 is mounted in the arms 12 of the bell cranks 11-12 and beneath the boat 5 and longitudinally of the latter, and to the member 110 is secured at one end by pin 111 a toothed wheel 112 85 adapted to be engaged by a dog 114 formed upon one end of a locking bar 113. This locking bar is mounted upon one end of the shaft 34. Due to the tension on all of the lashings, the tubular member 110 tends to rotate in a 90 clockwise direction. This action is resisted by the dog 114. When the davit is released and starts to move downwardly, the dog 114 rotates the toothed wheel 112 in a clockwise direction which is the same direction as the 95 tension of the lashings tends to rotate said wheel. When the lashings are tightened and the boat and cover and associated parts are tied in normal inoperative position, the toothed wheel 112 is put under tension by a 100 wrench, or other suitable tool before the dog 114 is engaged therewith. An inner end portion 113' of the locking bar 113 extends beyond the shaft 34 and by reason of its engagement with the latch 36 prevents the locking bar 113 from falling downwardly, when the davit and tubular member 110 and associated parts have moved downwardly. The cover 105 lashings and the boat lashings are formed with eyes 117 and these are engaged by the 110 ends of pins 115 secured in the tubular member 110, the locked position of these lashings being when the pins 115 are in the substantially horizontal position shown in Figure 21. Upon the automatic turning of the tubular member 110 from the position shown in Figure 21 to the position shown in Figure 22, the lashing eyes 117 engaged by the then lower ends of the pins 115 are released by reason of the lashing falling by gravity away from 115 said lower ends of the pins 115. The lashings 116 engaged by the upper ends of the pins 115 will be released by the pull of the cover 60, to which the cover-lashings and boat-lashings are respectively secured at 120 their upper ends, during the downward tilt-

ing movement of the rock arms 11-12, since the cover 60 remains suspended from the boom 8, and the tubular support 110 rocks away from the boom, as the latter moves outwardly. In this form of device, any manual release of the lashings before starting the launching movement is unnecessary since the pull of the lashings tends to assist the movement of the davit, instead of the davits necessarily having extra energy to pull the hooked rod 66 out of the lashing eyes, as is true of the form of construction shown in Figure 8.

In the form of boat-launching device shown and described, the davit, when the latches 36 are unfastened, tends to move downwardly, in a counter-clockwise direction, in the disposition of the parts shown in the accompanying drawings. This action, Figure 1, causes the bearing surface 52 of the curved outer end 9 of the davit to be moved to and held against the stop block 21, which would restrain the davit from further movement except as the cables 20 are played out. As a matter of fact, during the normal operation of the device, the cables 20 commence to play out immediately, and in a manner regulated by the control mechanism. The chocks 17 and 18 carry the boat 5 in its normal position and the weight of the boat 5 on these chocks is carried through the hinge pin 13, thus causing the rollers 14 to bear against the blocks 10. The weight of the boat 5 gives a counter-clockwise rotation to the rock arm 11-12 about the axis of the rollers 14. Since the pin 13 is mounted both in the boom 8 and the boat support 11-12, it is carried to the left, Figure 1, giving a counter-clockwise rotation to the davit about the pivot pin 6. This movement of the davit increases the distance between the pulleys 23 and 24 until all the slack is taken out of the cable between the surface 52 and the stop block 21. The arm 11 of the support member 11-12 is made considerably shorter than the arm 12, so that the movement of the pivot pin 13 to the left causes the arm 12 to drop rapidly, thus increasing the distance between the bearing surface 52 upon the under side of the curved portion 9 of the boom 8 and the chocks 17 and 18. The cable portion 20' of the operating cable 20 being of fixed length, the load is thus transferred to it.

The weight of the boom 8 and the crank arm 12 and associated parts adds to the rotating force in a counter-clockwise direction upon the upper ends of the booms 8, when the latches 36 are released. The force exerted by the pin 13 upon the boom in a counter-clockwise direction acts at the starting only of the boom rotation, inasmuch as the crank arm 12 drops away quickly from the under side of the boat 5.

In order to make certain that the stop block 21 remains in contact with the boom under surface portion 52 and does not lower 130

vertically relative to the boom 8 until the latter has completed its outward movement, the pulleys 22, 23, and 24 are so located relative to each other and to the pivot pins 6, that the moment arm M—2, Figure 1, is greater than the moment arm M—1. When the cables 20 are restrained from paying out by the hoisting mechanism, the weight of the load, after the crank arm 11—12 has been removed, acts on the moment arm M—2. This is resisted by a force acting on arm M—1. Since arm M—1 is less than arm M—2, the force exerted on the end of arm M—1 must be greater than the weight of the load acting on arm M—2, if the boom 8 is to remain stationary. Since the cable 20 is free to move on the pulleys except as restrained by block 21 bearing on the surface 52, this additional force must be applied at this point 52. When the cables 20 are being played out, this internal force continues to hold the pin 21 and the boom surface portion 52 together, and the boom will complete its outward movement before the pin 21 and the surface portion 52 separate. Any location of the pulleys 22, 23, and 24 and pivot point 6 which will cause arm M—2 to be greater than arm M—1 will satisfy these conditions. It is evident that under certain conditions the pulley 23 may not be required.

Moment arm M—2 is not constant, but is the horizontal distance between lines drawn vertically from the groove of pulley 22 and the pin 6, so that any list of the vessel will affect arm M—2. A list of the vessel in counter-clockwise direction, in the assembly shown in the accompanying drawings, will increase arm M—2, and therefore, hold pin 21 more tightly against the surface 52, which action, of course, is desirable. A list of the vessel clockwise may decrease arm M—2 until it is less than arm M—1. However, the assembly is such that a launching can be effected against a back list of 30° or more inasmuch as the weight of the boat 5 imposed vertically on the support arm 12 rotates the boom 8 in a counter-clockwise direction until arm M—2 becomes greater than arm M—1, after which the launching action proceeds as if there was no list of the vessel.

In the assembly shown, two pulleys 22 and 23 are used in order to obtain the desired lengths of the moment arms M—1 and M—2. Under suitable conditions only one such pulley would be required; whereas, there are probably conditions where even more than two pulleys would be required.

In the design worked out and shown in the accompanying drawings, it is desirable to hinge the load-support 11—12 for three reasons, viz., (1) so that the load-support will drop clear of the life boat 5 and not interfere with the clean cut launching of the latter; (2) so as to multiply the rotating force on the boom at all times and especially

in case of a list in the ship; and (3) so as to cause the end 12' on the load-support arm 12 to be drawn more closely to the pivot pin 6 in order that said load-support end 12' may strike the deck 1, thus acting as a stop for the boom. This stop prevents excessive rotation of the boom in a simple manner. The boom could be stopped by a chain, stop blocks, or other suitable mechanism, where the particular conditions warrant.

The proportions of the design worked out and shown in the accompanying drawings require that the support 11—12 move relatively to the boom. However, other proportions would permit this support to be secured rigidly to the boom and still give the desired results and, where the conditions permit, such a fixing of the load-support would be highly desirable. Other conditions might make it desirable to pivot the load-support 11—12 from some fixed part of the vessel, such as the deck house 3, and then control its movement by slides, links, or other mechanism, from a point at or near the pin 13 on the boom.

It will be noted from the accompanying drawings that the boat 5 and the launching mechanism are high slung and that a minimum amount of deck space is utilized during the usual non-operating position of the said elements.

What I claim is:

1. A boat-launching device comprising a main support; a boat-lowering davit pivoted to said support; means for holding the davit in normal inoperative position; a boat cover; a boat support secured to the davit and adapted to support a boat when the davit is in inoperative position; lashings for the cover and lashings for the boat; locking means for the lashings carried by said boat support; means permitting the davit to move for the launching operation; and unitary means for unfastening the lashings actuated by movement of said boat support at the commencement of the launching operation.

2. A boat-launching device comprising a main support; a boat-lowering davit pivoted to said support; means for holding the davit in normal inoperative position; a boat cover attached to the davit; lashings for the cover and lashings carried by the davit for the boat; locking means for the lashings; means permitting the davit to move for the launching operation; and unitary means connected to said locking means and to said main support for unfastening the lashings by the commencement of the launching operation, the boat cover remaining attached to the davit when removed from the boat.

3. A boat-launching device comprising a main support; a boat-lowering davit pivoted to said support; means for holding the davit in normal inoperative position; a boat cover; lashings for the cover and lashings for the

boat; locking means for the lashings; means permitting the davit to move for the launching operation; unitary means for unfastening the lashings; and means for removing the cover from the boat, said unfastening and removing means being controlled by a common means.

4. A boat-launching device, as set forth in claim 3, and further characterized in that the unfastening means are connected to the main support and the davit for automatic actuation by the outward movement of the davit.

5. A boat-launching device comprising a main support; a boat-lowering davit pivoted to said support; means for holding the davit in normal inoperative position; a boat cover; lashings for the cover and lashings for the boat; locking means for the lashings; means permitting the davit to move for the launching operation; unitary means for unfastening the lashings; and means for removing the cover from the boat, said unitary means including a movable element of fixed length secured both to the main support and to the davit, and also secured to the locking means.

6. A boat-launching device, as set forth in claim 3, and further characterized in that a tension-release device is provided for said movable element.

30 7. A boat-launching device comprising a main support; a boat-lowering davit pivoted to said support; means for holding the davit in normal inoperative position; a boat cover; lashings for the cover and lashings for the boat; locking means for the lashings including eyes on the lashings and a davit-supported bar having eye-cooperating hooks; means permitting the davit to move for the launching operation; and means for unfastening the lashings and removing the cover from the boat, the unfastening means including a movable element of fixed length secured both to the main support and to the davit and also secured to the bar of said locking means.

45 8. A boat-launching device, as set forth in claim 7, and further characterized in that said movable element is a cable secured to the bar of said locking means.

9. A boat-launching device comprising a main support; a boom pivoted to said support; means for lowering the boom; a cable engaging the boom and adapted to carry the boat during launching; means for regulating the cable movements; a boat cover; lashings for the cover and lashings for the boat; locking means for the lashings; means for unfastening said locking means; and means automatically actuating said unfastening means at the commencement of the boom movement.

50 10. A boat-releasing device comprising a main support; a boom mounted upon said support; a cable engaging the boom and adapted to carry the boat; a boat cover; lashings for the cover and lashings for the boat;

unitary locking means for the lashings; and unitary means for unfastening said locking means.

55 11. A boat-launching device comprising a main support; a boom pivoted to said support; means for lowering the boom; a pulley mounted on the boom; a cable engaging said pulley and adapted to carry the boat during launching; means for regulating the cable movements; a boat cover; lashings for the cover and lashings for the boat; unitary locking means for the lashings; means for unfastening said locking means; and means automatically actuating said unfastening means at the commencement of the outward movement of the boom.

60 12. A boat-launching device comprising a main support; a boom pivoted adjacent its lower end to said support and adapted to move outwardly under the force of gravity; a boat-support; means for moving the latter relative to the boat upon the outward movement of the boom; a cable engaging the boom and adapted to carry the boat during launching; means for regulating the cable movements; means for detachably locking the boom in raised position to the main support; a boat cover; lashings for the cover and lashings for the boat; locking means for the lashings carried by said boat support; means for unfastening said locking means; and means automatically actuating said unfastening means at the commencement of the boat-support movement.

65 13. A boat-launching device comprising a main support; a boom pivoted adjacent its lower end to said support and adapted to move outwardly under the force of gravity; a boat-support; means for moving the latter relative to the boat upon the outward movement of the boom; a cable engaging the boom and adapted to carry the boat during launching; means for regulating the cable movements; means for detachably locking the boom in raised position to the main support;

70 140 a boat cover; lashings for the cover and lashings for the boat; locking means for the lashings; means for unfastening said locking means; and means automatically actuating said unfastening means at the commencement of the boat-support movement.

75 14. A boat-launching device comprising a main support; a boom pivoted adjacent its lower end to said support and adapted to move outwardly under the force of gravity; a boat-support; means for moving the latter relative to the boat upon the outward movement of the boom; a pulley mounted on the boom; a cable engaging said pulley and adapted to carry the boat during launching;

80 145 means for regulating the cable movements; means for detachably locking the boom in raised position to the main support; a boat cover; lashings for the cover and lashings for the boat; unitary locking means for the lash-

ings; means for unfastening said locking means; and means automatically actuating said unfastening means at the commencement of the boom movement.

15. A boat-launching device comprising a main support; a boom pivoted to said support; means for lowering and raising the boom; a pulley mounted on the boom; a cable engaging said pulley and adapted to carry the boat during launching; means for regulating the cable movements; a boat cover; lashings for the cover and lashings for the boat; unitary locking means for the lashings; and means actuated by the boom and at the commencement of the outward movement of the boom for unfastening said locking means.

16. A boat-launching device comprising a main support; a boom pivoted adjacent its lower end to said support and adapted to move outwardly under the force of gravity; a boat-support; means for moving the latter relative to the boat upon the outward movement of the boom; a pulley mounted on the boom; a cable engaging said pulley and adapted to carry the boat during launching; means for regulating the cable movements; means for detachably locking the boom in raised position to the main support; a boat cover; lashings for the cover and lashings for the boat; unitary locking means for the lashings mounted on the boom and having a limited movement relative thereto; means secured to the main support and to the unitary locking means and adapted to unfasten the latter concurrently with a movement of the boom outwardly from the main support; and a tension-release device for said securing means effective when said locking means have made their limited movement relative to the boom.

17. A boat-releasing device comprising a main support; a boom mounted on said support; a pulley mounted on the boom; a cable engaging said pulley and adapted to carry the boat; a boat cover suspended from the boom; a plurality of cover lashings permanently secured to the cover and detachably secured to the boom; unitary locking means for said lashings; and means for unfastening the detachable lashing connections.

18. A boat-releasing device comprising a main support; a boom mounted on said support; a boat-support; means for moving the latter relative to the boat; a cable engaging the boom and adapted to carry the boat; a boat cover suspended from the boom; a plurality of cover lashings permanently secured to the cover and detachably secured to the boom; locking means for said lashings; and means for unfastening the detachable lashing connections.

19. A boat-launching device comprising a main support; a boom pivoted adjacent its lower end to said support and adapted to move outwardly under the force of gravity; a boat-support; means for moving the latter relative to the boat upon the outward movement of the boom; a pulley mounted on the boom; a cable engaging said pulley and adapted to carry the boat during launching; means for regulating the cable movements;

means for detachably locking the boom in raised position to the main support; a boat cover; lashings for the cover and lashings for the boat; unitary locking means for the lashings mounted on the boom; and means secured to the main support and to the unitary locking means and adapted to unfasten the latter concurrently with a movement of the boom outwardly from the main support.

20. A boat-launching device comprising a main support; a boom pivoted adjacent its lower end to said support and adapted to move outwardly under the force of gravity; a boat-support; means for moving the latter relative to the boat upon the outward movement of the boom; a pulley mounted on the boom; a cable engaging said pulley and adapted to carry the boat during launching; means for regulating the cable movements; means for detachably locking the boom in raised position to the main support; a boat cover; lashings for the cover and lashings for the boat; unitary locking means for the lashings mounted on the boom and having a limited movement relative thereto; means secured to the main support and to the unitary locking means and adapted to unfasten the latter concurrently with a movement of the boom outwardly from the main support; and a tension-release device for said securing means effective when said locking means have made their limited movement relative to the boom.

21. A boat-launching device comprising a main support; a boom pivoted adjacent its lower end to said support and adapted to move outwardly under the force of gravity; a boat-support; means for moving the latter relative to the boat upon the outward movement of the boom; a pulley mounted on the boom; a cable engaging said pulley and adapted to carry the boat during launching; means for regulating the cable movements; means for detachably locking the boom in raised position to the main support; a boat cover; lashings for the cover and lashings for the boat; unitary locking means for the lashings mounted on the boom; and means for unfastening the locking means and comprising a longitudinal housing mounted on the boom and forming a support for the locking means and within which the latter has a limited amount of movement, a cable secured to the main support and the locking means, and a tension-release device for the last-mentioned cable which is effective when the locking means have made their limited movement relative to said housing.

22. A boat-launching device comprising a main support; a boom pivoted adjacent its lower end to said support and adapted to move outwardly under the force of gravity; a boat-support; means for moving the latter relative to the boat upon the outward movement of the boom; a pulley mounted on the

- boom; a cable engaging said pulley and adapted to carry the boat during launching; means for regulating the cable movements; means for detachably locking the boom in raised position to the main support; a boat cover; lashings for the cover and lashings for the boat; unitary locking means for the lashings mounted on the boom; and means for unfastening the locking means and comprising a longitudinal housing mounted on the boom and forming a support for the locking means and within which the latter has a limited amount of movement, a cable secured to the main support and the locking means, a pulley around which said last-mentioned cable passes, said pulley being mounted upon said locking means; and means for dismounting said pulley from the locking means after the lashings have been released and before the locking means have completed their limited amount of movement relative to the housing.
23. A boat-launching device comprising a main support; a boom pivoted adjacent its lower end to said support and adapted to move outwardly under the force of gravity; a load-support secured to the boom and movable relatively to the latter upon the outward movement of the boom; pulleys mounted on the boom; a cable engaging the pulleys and adapted to carry the load; means for regulating the cable movements; means for detachably locking the boom in raised position to the main support; and a stop bracket for rigidly fixing the load support relative to the boom after the latter has moved a predetermined distance.
24. A boat-launching device comprising a main support; a boom pivoted adjacent its lower end to said support and adapted to move outwardly under the force of gravity; a load-support secured to the boom and movable relatively to the latter upon the outward movement of the boom; pulleys mounted on the boom; a cable engaging the pulleys and adapted to carry the load; means for regulating the cable movements; means for detachably locking the boom in raised position to the main support; and a bracket secured to said load-support and adapted to engage the boom, to stop the movement of the load-support relative to the boom, after the latter has moved a predetermined distance.
25. A boat-launching device comprising a main support; a boom pivoted adjacent its lower end to said support and adapted to move outwardly under the force of gravity; a load-support secured to the boom and movable relatively to the latter upon the outward movement of the boom, said relative movement being downwardly toward a ground-engaging position of the load-support; pulleys mounted on the boom; a cable engaging the pulleys and adapted to carry the load; means for regulating the cable movements; means for detachably locking the boom in raised position to the main support; and a stop bracket for rigidly fixing the load support relative to the boom after the latter has moved a predetermined distance.
26. A lashing-release device, for use with life boats, comprising, in combination with a boat cover and boat-lashings and cover-lashings, unitary locking means for the lashings, and unitary means for unfastening the lashings.
27. A lashing-release device, for use with life boats, comprising, in combination with a boat cover and boat-lashings and cover-lashings, locking means for the lashings; means for unfastening the lashings; and means for automatically actuating the unfastening means, said last-mentioned means including a movable element of fixed length adapted to be secured to the unfastening means and to a fixed support, and said unfastening means being adapted for mounting on a movable davit.
28. A lashing-release device, for use with lift boats, comprising, in combination with a movable davit, a boat cover attached thereto; combined boat-lashings and cover-lashings connected to said davit; locking means for the lashings; and means for unfastening the lashings, the unfastened lashings remaining attached to the davit.
29. A lashing-release device, for use with lift boats, comprising, in combination with a pivoted davit, and boat lashings; locking means for the lashings; and means controlled by the movement of the davit for unfastening said locking means.
30. A lashing-release device, for use with life boats, comprising, in combination with a pivoted davit, a boat cover and boat-lashings and cover-lashings; locking means for the lashings; and unitary means controlled by the movement of the davit for unfastening said locking means.
31. A lashing-release device, for use with life boats, comprising, in combination with a davit, a boat cover, boat lashings attached to said cover and cover-lashings, said cover being attached to the davit; unitary locking means for the lashings; and means for unfastening the lashings, the cover remaining attached to the davit and the lashings remaining attached to the cover, when the lashings are released from said locking means.
32. A lashing-release device, for use with life boats, comprising, in combination with a davit, means for mounting a life boat therein in high-slung condition, a boat cover attached thereto, and boat lashings and cover lashings; unitary locking means for the lashings; and means for unfastening the lashings, the unfastened lashings remaining attached to the davit.

33. A lashing-release device, for use with lift boats, comprising, in combination with a pivoted davit, means for mounting a lift boat therein in high-slung condition, and boat lashings; locking means for the lashings; and means controlled by the movement of the davit for unfastening said locking means.

Signed by me this 2nd day of August, 1930.

CERTIFICATE OF CORRECTION.

Patent No. 1,827,535.

Granted October 13, 1931, to

ANGUS D. MCKENZIE.

It is hereby certified that error appears in the printed specification of the above numbered patent requiring correction as follows: Page 3, line 10, for the word "of" read and; page 6, line 117, claim 2, strike out the words "carried by the davit" and insert the same to follow the word "lashings" in line 118; page 7, line 27, claim 6, for "3" read 5; page 9, lines 91 and 99, claims 28 and 29, and page 10, lines 2 and 3, claim 33, for "lift" read life; and that the said Letters Patent should be read with these corrections therein that the same may conform to the record of the case in the Patent Office.

Signed and sealed this 22nd day of December, A. D. 1931.

(Seal)

**M. J. Moore,
Acting Commissioner of Patents.**
